UNITED STATES PATENT OFFICE.

CHARLES T. GOODE, OF WASHINGTON, DISTRICT OF COLUMBIA, AND OTTO KELLEY, OF BLUEMONT, VIRGINIA.

FORM CLAMP.

Application filed March 27, 1926. Serial No. 97,931.

This invention relates to form clamps for clamping forms for concrete work and particularly to form clamps for column or beam forms.

- 5 An object of the invention is to provide an improved form clamp for column and beam forms. Another object is to provide a form clamp that can be put in place and tightened by one person without assistance. 10 Another object is to provide a clamp that will eliminate the use of timbers or cleats to hold the parts of the form in place or to prevent the clamps from slipping on the form. Still another object is to provide a 15 form clamp all the parts of which are permanently secured together so that the parts can not be separated or lost while being transported from job to job. Other objects will be in part obvious and in part brought 20 out in the following specification and appended claims.

In the accompanying drawings in which we have shown for the purpose of illustration, the preferred embodiment of our invention.

In the drawings,—

Figure 1 is a plan view of our clamp as applied to a column.

Fig. 2 is a front elevation of the clamp 30 as applied to a column.

Fig. 3 is a view of our clamp as applied to a beam.

Fig. 4 is a view of the corner showing the manner of securing the clamping action.

35 In these drawings numerals 1, 2, 3, and 4 indicate the sides of an ordinary column mold, in this case of square cross section but the clamp may equally well be applied to forms of rectangular section or the clamps 40 may be made with a larger number of side pieces as for instance six or eight sides to clamp forms having that number of sides. The side members of the clamp are indicated at 5, 6, 7, and 8. These side members are 45 composed of strips of angle iron notched and slotted as will hereinafter appear and permanently joined at all but one corner by means of links 9. These links 9 are preferably formed of rod or wire bent to shape 50 and the ends welded after assembly of the clamp although we also consider using what are known to the trade as open links for uniting the smaller size clamps. Those ends of the clamp members which are united or

joined to the adjacent clamp members by 55 means of the links 9 we call the closed ends of the members, while the end which can be opened to permit the clamp to be placed on the form we call the open end of the members.

60 The sides of the clamp are made adjustable to any desired size by means of the series of notches 12 in the edge of the flange of the angle member which is perpendicular to the side of the form, which notches are 65 selectively engaged for any desired setting by the links 9. The contacting flanges of the angular clamping members are cut away as at 13 to provide slots for the links 9 to slide in, in order that the links may move 70 to engage the various notches 12.

75 The open corner of the clamp is closed by means of a latch which is formed as follows; the outer edge of the perpendicular flange of the open end of the member 5 is provided with a slant edge as shown at 17, in this flange is a series of holes 11 to receive a fastening pin 10. The holes 11 are on a line parallel with the slant edge 17 for a purpose later to appear. The flange of the member 8 which contacts with the form is provided with a slot 18 similar to the notches 13 but of very much less length as it does not have to allow for longitudinal adjustment as do slots 13. The perpendicular flange is provided with a hole 80 14 adjacent the contacting flange and spaced from the outer end of the slot 18 a distance equal to the distance from the slant edge 17 to the holes 11 so that when the perpendicular flange of the member 5 is passed through 85 the slot 18 the holes 11 and the hole 14 will coincide in such a manner that a pin 10 may be passed through the aligned openings to 90 lock the clamp in place. The holes 11 and 14 are preferably made of the proper size 95 to receive an ordinary spike nail as these nails are always to be found on the job and make a very cheap and efficient fastening pin and has the additional advantage of being easy to remove when it is desired to remove the 100 clamp from the form, also the head serves as a retaining means to prevent the pin from slipping through the holes and releasing the clamp prematurely. The slot 13 of the open end of the member 5 is continued to the end 105 of the member to provide an opening instead of a closed end as true of the closed end of the members. This opening allows the per-

pendicular flange of the member 5 to be passed through the slot 18 of the member 8.

The operation of our device is as follows: the column being assembled either in place or on a jig, the member 5 is placed on a side of the form, as side 1, and adjusted in such a manner that one of the holes 11 is spaced from the edge of the form by a distance equal to the thickness of the contacting flange of member 8. The member 5 is then tacked to the side of the form by means of short nails 16 passing through holes 15 provided in the contacting flange of the form members for the reception of such nails. 15 The holes 15 are not counter sunk but left straight to facilitate access to the heads of the nails to enable them to be easily removed.

After the member 5 has been tacked in place the link 9 connecting the members 5 and 6 is adjusted longitudinally to engage one of the notches 12 to allow the member 6 to be pressed against the side 2 by a light pressure, the member 7 is likewise adjusted and pressed into place which clamps side 25 2 between members 5 and 7 with the links 9 and member 6 in tension. Member 8 is then put in place with the slot 18 over the perpendicular flange of member 5 and then driving the end of member 8 down against the side 4 of the form, the end of the slot 18 rides up the slanting edge 17 pulling the member 8 which in turn pulls the link and through it the member 7 so that each part of the clamp is under tension whereby the form 35 is thoroughly bound together.

To apply the clamp to a beam form the element 5 is swung around out of the way as clearly shown in Fig. 3, and member 7 passed under the bottom of the form, the 40 links 9 are then adjusted so that considerable force is necessary in order to press members 6 and 8 against the sides of the form after which they are held in place by the usual straining wires 19.

45 Frequently one side of the beam form must be lower than the other in order to allow the casting of a floor slab integral with the beam. This is readily taken care of by my adjustable corners which allow one member to have a very short effective length while the other side has a long effective length.

Having thus described our invention, we

claim as new and desire to secure by Letters Patent—

55

1. A clamp for concrete forms comprising a plurality of side members of angular cross section, one of the flanges of the angle being adapted to contact with the side of the form while the other flange is adapted to be at right angles to the said form, the said contacting flanges being cut away adjacent the ends thereof to provide longitudinally extending slots, one side of said slot being in the plane of the inner surface of the perpendicular flange, links permanently connecting the said side members at all but one of the corners of the clamp, the said links passing through the said slots and embracing the said perpendicular flange of the two adjacent side members, the said perpendicular flanges being provided with notches on the outer edges thereof to selectively engage the said links, and a latch to releasably fasten the remaining or open corner.

75

2. A clamp for concrete forms of rectangular cross section comprising a plurality of side members, links permanently connecting the said side members together, said links being adjustable longitudinally along the 80 side members to adapt the clamp to any size form, and means comprising a cam surface on the free end of one member, a slot in the free end of the opposite member, and cooperating pin receiving openings, to releasably 85 connect the open ends of the clamp.

5

3. A clamp for concrete forms comprising rigid side members, links to permanently connect said rigid side members at all but one of the corners of the clamp, means on 90 said rigid side members to adjust their effective length and releasable means to fasten the remaining corner.

10

4. A clamp for concrete forms comprising rigid side members, rigid links permanently and adjustably connecting the said rigid side members at all but one corner of the clamp so that the parts may not be separated or lost, means integral with the side members to tighten the clamp on the form and means to permit locking the clamp in place.

95

In testimony whereof, we have hereunto set our hands this 26th day of March, 1926.

CHARLES T. GOODE.

OTTO KELLEY.
